UNITED STATES PATENT OFFICE.

WILLIAM F. RIKER, OF NEWARK, NEW JERSEY.

DESIGN FOR A BRIDLE-ROSETTE.

SPECIFICATION forming part of Design No. 16,596, dated March 30, 1886.

Application filed March 5, 1885. Serial No. 157,858. Term of patent 7 years.

To all whom it may concern:

Be it known that I, WILLIAM F. RIKER, a citizen of the United States, residing at Newark, in the county of Essex and State of New Jersey, have invented and produced a new and original Design for Bridle-Rosettes; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In said drawings, Figure 1 is a plan of the rosette, and Fig. 2 is a side elevation of the same, said figures being deemed sufficient to illustrate the nature of the design, the leading feature of which consists in a bridle-rosette having a faceted jewel projecting directly from the plane, smooth, or uncorrugated or unembossed front surface of a disk-shaped portion, there being no comparatively deep annular recess between said faceted and plane surfaces, and having an oblong loop on the opposite side of said disk-shaped portion.

In said drawings, *a* is the plane, smooth, or uncorrugated or unembossed surface of the disk-shaped portion; *b*, an oblong angular loop, and *c* a projecting jewel having faceted surfaces *d d*, which are raised directly from the plane surface, there being no deep recess around the jewel between it and the plane surface, as in certain buttons for garments of which I am aware.

What I claim as new is—

The design for a bridle-rosette herein described, consisting of a bridle-rosette having a disk-shaped portion with oblong angular loop on one side, and on the opposite side a plane, smooth, or uncorrugated surface, with a projecting faceted surface at the center extending directly from said plane surface, as set forth.

In testimony that I claim the foregoing I have hereunto set my hand this 12th day of February, 1885.

W. F. RIKER.

Witnesses:

CHARLES H. PELL,
OSCAR A. MICHEL.
